UNITED STATES PATENT OFFICE.

THOMAS H. CAMPBELL, OF TEMPLE, TEXAS.

PHONOGRAPH ATTACHMENT.

Application filed June 20, 1922. Serial No. 569,637.

To all whom it may concern:

Be it known that I, THOMAS H. CAMPBELL, a citizen of the United States of America, residing at Temple, Texas, have invented 5 a new and useful Phonograph Attachment, of which the following is a specification.

My invention relates to an attachment for phonographs and more particularly to a tone modifier to be secured to the needle 10 bar of a phonograph sound box or reproducer whereby the transmitted vibrations are affected and the tone produced modified.

It is the general object of the invention 15 to provide a simple and serviceable tone modifier for a phonograph whereby the tones produced are softened or modified.

In the preferred form of my invention the tone modifier is formed of a block preferably of metal. One or more grooves are 20 formed in the block, which grooves are adapted to fit over and engage the needle bar of an ordinary reproducer or sound box. Each groove in the tone modifier block is 25 of irregular shape, preferably curved, so that when the groove is fitted over the needle bar the latter will be slightly deflected and the tone modifier will be frictionally held thereon.

30 In the drawings, illustrating a preferred form of the invention and forming part of this specification—

Fig. 1 is a front elevation of a sound box or reproducer having a tone modifier applied to the needle bar.

Fig. 2 is a side elevation of the parts shown in Fig. 1, a part being broken away to show the diaphragm and adjacent end of the needle bar.

40 Fig. 3 is a perspective view of a tone modifier showing somewhat diagrammatically a fragment of a needle bar in place.

In said drawings, 5 indicates the body portion of a conventional type of reproducer or sound box, and 6 indicates the usual diaphragm therein. The sound box or reproducer is provided with a needle bar 7 which is pivoted at 8 to a lug 9 on the sound box. One end of the needle bar 45 carries the needle 10 while the opposite end is secured to the diaphragm 6 at 11. The

needle bars of sound boxes of the present type are relatively thin as indicated particularly in Fig. 1.

In order to soften or modify the tone 55 produced in the phonograph I have provided novel means for attachment to the needle bar for varying the vibrations therein and thus modifying the tones produced. In the specific form shown the tone modifier is in the form of a block 12 preferably 60 formed of metal such as brass, though the specific material of which the tone modifier is made is not in all cases material. In the block I have indicated three grooves 65 13, 14, 15 and these grooves are preferably 70 are shaped or curved so as to be of irregular shape. These grooves are of varying widths to accommodate needle bars of varying thicknesses on sound boxes of different types 75 or make. While the grooves shown are all in one face of the rectangular block, it should be understood that this arrangement is not necessary for the grooves might be otherwise disposed.

When it is desired to modify the tone 80 produced in the sound box the tone modifier is applied to the needle bar preferably by placing the end of the groove of the proper size over the needle bar adjacent 85 its inner end and then sliding the block along the needle bar toward the periphery of the sound box. If the grooves are of irregular shape the needle bar will be slightly deflected and the tone modifier will be frictionally held thereon. Due to the modification of the effective vibrating portions 90 of the needle bar when the tone modifier is adjusted, the tones produced will be materially modified and softened.

While I have illustrated and described a preferred form of my invention, I wish it understood that various modifications and changes may be made within the scope of the appended claim.

I claim:

As an article of manufacture, a tone modifier to be applied to the needle bar of a phonograph sound box comprising a block of substantially rigid material having 100 a groove therein of tortuous form.

THOMAS H. CAMPBELL.
